UNITED STATES PATENT OFFICE.

CHARLES DRUM, OF CALIFORNIA, PENNSYLVANIA.

AUTOMATIC GATE MECHANISM FOR ELEVATOR AND MINE SHAFTS.

1,423,919.

Specification of Letters Patent. Patented July 25, 1922.

Application filed December 19, 1919. Serial No. 346,036.

To all whom it may concern:

Be it known that I, CHARLES DRUM, a citizen of the United States, residing at California, in the county of Washington and 5 State of Pennsylvania, have invented a new and useful Improvement in Automatic Gate Mechanism for Elevator and Mine Shafts, of which the following is a full, clear, and exact description.

10 The present invention relates broadly to gates and operating mechanism therefor, but more particularly to mine gates and the like adapted to be automatically controlled by the elevator or cage. 15 It has heretofore been proposed to provide a plurality of elevator gates with mechanism for automatically controlling the same by the position of the elevator. Such arrangements as heretofore provided have not, 20 however, embodied certain safety features which have been found highly desirable, and they have not provided a single operating means for all of the gates, so connected as to normally maintain a predetermined driving 25 connection with respect to one of the gates while permitting operation to establish driving connection with any one only of the gates at the same time.

By the present invention, I have provided 30 a gate-operating mechanism embodying certain of the above desirable features, and electrically controlled, whereby operation of the actuating motor can not occur until an operative connection with the desired gate 35 has been established. Another object of the present invention is to so retard the operation of certain of the parts that certain operations can only occur under proper conditions.

40 The foregoing and other objects, together with their attendant advantages, will be apparent as the invention becomes better understood by reference to the accompanying specification and drawings forming a part 45 thereof, it being premised that changes may be made in the various details and the manner of operation within the scope of the appended claims without departing from the spirit of the invention.

50 Figure 1 is a diagrammatic illustration of the operating motor for a plurality of gates and the various connections therefor.

Figure 2 is a wiring diagram illustrating in heavy lines the circuits energized for 55 opening the gate for one of the shafts.

Figure 3 is a view corresponding to Fig-

ure 2, illustrating the circuit connections when the gate is being closed.

Figure 4 is a similar view illustrating the circuit connections when one of the gates for 60 another of the shafts is being opened.

Figure 5 illustrates the circuit connections for closing the last mentioned gate, and

Figures 6, 7, 8 and 9 are enlarged detail 65 views illustrating slightly modified types of gates.

The present invention is directed particularly to providing a system of gate control for mine shafts, which control is such that the gates are operated by the cages as required by the bituminous mine laws of certain of the States.

As illustrated in the drawings, the invention is particularly applicable to a plurality of gates provided on adjoining shafts, which 75 gates are controlled by a common motor. The invention is, however, not limited in this particular, and may in several respects be applied to the operation of a single gate as will be apparent hereinafter.

Referring more particularly to the drawings, there is illustrated a motor 2, preferably of the direct current reversible type, having an armature shaft 4 extending beyond the opposite sides of the motor casing 80 and carrying on one end a member 5 constituting one part of a clutch driving connection, and on the opposite end a similar member 6, constituting one portion of a second driving connection. The member 5 is 85 normally held in engagement with its cooperating member 7 by a suitable spring device 3, whereby a normal operative driving connection is provided between the motor and the member 7. This member is in turn 90 carried on one end of a shaft 8 having a suitable bearing 9 and carrying at its opposite end a gear 10 meshing with a reduction gear 11 on the shaft 12. The shaft 12 may be journaled in any desired bearings 100 14 and is provided with pinions 15 meshing with racks 16 connected to the gate 17 employed in connection with the elevator or cage A.

In like manner, the member 6 is adapted 105 to engage its cooperating member 18, carried on one end of the shaft 19 journaled in the bearing 20 and provided on its opposite end with a spur gear 21. This spur gear meshes with a reduction gear 22 on the shaft 24 110 journaled in the bearings 25 and provided with pinions 26 meshing with racks 27 on the

gate 28 for the cage or elevator B. As shown, this second clutch is normally in inoperative position. Each of the gates 17 and 28 are illustrated as provided with suitable counterbalancing weights 29 arranged in any desired approved manner.

For rendering the normal operative driving connection between the motor and the gate 17 inoperative, and rendering the cor-

- 10 responding normally inoperative driving connection between the motor and the gate 28 operative, I have provided a clutch actuating mechanism. This mechanism comprises a suitable lever 30 having a pivotal mounting 31 at one end and cooperating at its other end with a collar 32 formed on the clutch member 5. Intermediate its ends, it is connected by a link 34 with a similar lever 35 having a pivotal mounting 36 for one end and cooperating at its opposite end with the collar 33 on the clutch member 6. The lever 35 is in turn adapted to be operated by a bell crank 37 having a link connection 38 with a second bell crank 39. This second 25 bell crank is operatively connected by the rod 40 with the core 41 of a solenoid 42. The solenoid is preferably connected to a dash-pot 44 in such manner that the forward movement of the core 41 to produce 30 the operation of the clutches described, is retarded. The dash-pot may be so adjusted that a time interval of approximately three seconds is required for the movement of the solenoid core. This solenoid is controlled 35 by the movement of the cage B, as will be more fully described hereinafter.

40 Mounted on the cage A is a switch operating member 45 adapted to contact at a certain position of the cage with the arm 46 carrying a circuit-closing arm 47. The arm 46 is so located in the shaft that the member 45 will be brought into engagement therewith when the cage A is at one of the floor levels. Assuming that the cage A has 45 reached such a position, the gate 17 will be opened in the following manner: Current will flow through the line wire L to the branch connection 48 of the solenoid 49, the opposite end of which is joined by a 50 conductor 50 with the switch point 51. With the short circuiting arm 46 in closed position, current will flow from the point 51 through the conducting plate 47 to the point 52, and thence through the line wire L', 55 completing the solenoid circuit. This solenoid is provided with a core 54 carrying crossheads 55 and 56, and connected to a dash-pot 57 corresponding generally to the dash-pot 44 for the solenoid 42, and prefer- 60 ably adjusted to require a time interval of five seconds for the movement of the core 54. The solenoid 49 having been energized, if the cage A remains at a floor level for a period of at least five seconds, the core 54 65 will be lifted to close the circuit to the mo-

tor 2. Current will now flow from the line wire L to the switch point 58, thence through the conducting plate 59 to the switch point 60 and wire 61 to one side of the motor 2. On the opposite side of the motor the circuit is completed through the wire 62 to the switch point 63, conducting plate 64, switch point 65 and wire 66 to the switch point 67. Normally cooperating with the switch point 67 and its cooperating point 68 is a short circuiting switch 69 held in short circuiting position by a suitable spring 70. This switch is provided with a projecting arm 71 adapted to be engaged by a projection 72 on the gate 17, as will be more fully described hereinafter.

70 From the switch point 68 the current will flow through the wire 74 to the switch point 75, conducting plate 76 on the cross head 56 to the switch point 77 and thence through the wire 78 to the switch point 79. This switch point and its cooperating switch point 80 are normally short circuited by a suitable switch carrying a conducting plate 81 held in short circuiting position by a spring 82 and provided with an arm 84 adapted to be engaged by the projection 85 on the gate 28 as described in detail in connection with said gate. From the switch point 80, the current 85 flows through the wire 86 to the line wire L', thereby completing the motor circuit and causing the motor to open the gate 17 through the operative driving connection described. After the gate 17 has reached 90 its full open position, the projection 72 will engage the arm 71 and open a switch cooperating with the points 67 and 68 thereby breaking the motor circuit. The gate will remain in its open position until the cage A 95 moves away from engagement with the arm 46. When such movement of the cage occurs, the circuit for the solenoid 49 will be broken and the current will be conducted to the motor 2 in such manner that it will be 100 rotated in the reverse direction for closing the gate 17. By referring more particularly to Figure 3, the circuit connections for producing this operation will be apparent. The circuit for the solenoid 49 having been 105 broken, the core 54 will drop to its lower position so that current will flow through the line wire L to the switch point 87, conducting plate 88 on the cross head 55 to the switch point 89 and thence through the wire 110 62 to one side of the motor 2. From the opposite side of the motor the circuit will be completed through the wire 61 to the switch point 90 and thence through the conducting plate 91 to the switch point 92, 115 wire 94, switch point 95, conducting plate 96, switch point 97 and wire 98 to the switch point 99. This switch point is normally connected to its cooperating switch point 100 by a short circuiting plate 101 on 120 125 130

a suitable switch normally held in engagement with the switch points by a spring 102 and provided with an arm 103 adapted to be engaged by the projection 72 on the gate 17 when the gate reaches its closed position. From the switch point 100 the current flows through the wire 104 to the line wire L'. From the connections described it will be apparent that the motor 2 has its terminals connected to the line wires so that the current flow is in the opposite direction from the flow which occurs with the circuit connections as described in Figure 2, thereby reversing the direction of rotation of the motor to close the gate 17. This rotation will continue until the projection 72 on the gate engages the arm 103 to break the circuit between the switch points 99 and 100. It will be apparent that the number of gates and the number of operating motors may be increased to any desired number corresponding to the number of the floor levels entering the shaft.

The cage B is adapted in a somewhat similar manner to control the operation of the gate 28. One of these gates 28 is also preferably positioned adjacent each floor level intersecting the shaft in which the cage B operates. Assuming the cage B to have reached a position adjacent one of the floor levels, the member 105 will engage the arm 106 carrying the short circuiting switch member 107, moving this member to the position illustrated diagrammatically in Figure 4. In this position, current will flow through the line wire L to the wire 48 and thence through the solenoid 49, wire 50 to wire 108 and thence to the switch point 109. From the switch point the current will flow through the conducting plate 107 to the switch point 110 and wire 111 to the line wire L'. The solenoid 49, having been energized, will lift its core 54 and the cross heads 55 and 56 carried thereby. Previous to the complete operation of the core 54, the core 41 of the solenoid 42 will have been lifted to disconnect the clutch members 5 and 7 and bring into operative driving engagement the clutch members 6 and 18. This operation will occur due to the fact that a time interval of but three seconds is required for the operation of the core 41, while a time interval of approximately five seconds is required for the operation of the core 54. The circuit for the solenoid 42 is completed through the line wire L to branch wire 112 connected to one side of the solenoid, and thence through the wire 114 connected to the opposite side thereof, to the switch point 115. From this switch point the current will flow through the conducting plate 107 to the switch point 110 and thence through the wire 111 to wire 86 and to the line wire L'. It will now be apparent that the clutch members 6 and 18 are in driving engagement so that upon rotation of the motor, the gate 28 will be opened. The motor circuit is completed through the line wire L and wire 61, as described in connection with Figure 2. The opposite side of the motor is connected through wires 62, 66, 70 74, 78 and 86 to the line wire L'. The gate will continue this opening movement until the projection 85 engages the arm 84 at which time the motor circuit will be broken. The gate will remain in its open position 75 until the cage B moves from the floor level, at which time the circuit connections will be as shown more particularly in Figure 5 to insure the closing of the gate. The solenoid 49 will have its circuit broken thereby permitting the core 54 to drop to its lower position. The solenoid 42 will, however, remain in circuit with the line wire L, wire 112 and wire 114 with the switch point 116. This switch point is normally engaged by the 80 conducting plate 117 on a suitable switch provided with an arm 118 adapted to be engaged by the projection 85 on the gate 28 when the gate 28 reaches its closed position. As soon as the gate leaves the said position, 85 a suitable spring 119 is provided for forcing the conducting plate 117 into engagement with the switch point 116. This condition having been established due to the opening of the gate 28 as described in connection with 90 Figure 4, current will flow from the switch point 116 to the switch point 120 and thence through the wire 121 to the wire 86 leading to the line wire L'. This will hold the clutch members 6 and 18 in engagement so that the 95 reverse rotation of the motor will close the gate 28. This rotation of the motor is secured by current flowing from the line wire L to the wire 62 connected to one side of the motor, as described more particularly in 100 connection with Figure 3. From the opposite side of the motor the current will flow through the wires 61, 94 and 98 to the wire 122 connected to the switch point 124. From 105 this switch point the current will flow through the conducting plate 117 to switch point 125 and thence through wires 121 and 86 to the line wire L'. From the circuit connections described, it 110 will be apparent that if either of the gates is in open position, the other gate cannot be operated. This provides a safety system complying with the bituminous mine laws of certain of the States. At times, however, it may be desirable to manually control either 115 the gate 17 or the gate 28 and for this purpose we provide a knife switch 126 adapted to short circuit the points 51 and 52 in the same manner that this operation is produced by the conducting plate 47. I also preferably provide a second switch 127 for short circuiting the points 109, 115 and 110. 120 In the construction so far described, the gates have been adapted to move vertically when operated by the motor. In some in- 125 130

stances it may be desirable to have the gates slide horizontally and I have illustrated such a construction in Figure 6. The shaft 24^a, corresponding to the shaft 24, is provided with a bevel gear 130 meshing with a similar gear 131 on the shaft 132. This shaft has splined thereto a pinion 134 meshing with the rack 135 carried by the gate 17^a.

In Figure 7 I have illustrated a gate 17^b having a pivotal mounting 136. Concentric with this mounting is a worm wheel 137 adapted to be driven by the worm 138 on the shaft 24^b. When the motor is operated, this gate will be swung into and out of position in a vertical direction.

In Figures 8 and 9 there is illustrated a gate 17^c adapted to swing about a vertical axis 139 concentric with which is a worm wheel 140 adapted to be driven by the worm 141, on the outer end of the shaft 24^c.

It will be apparent that the particular type of gate employed may be changed to suit the conditions.

The advantages of this system arise from the provision of time elements connected to the solenoids in such manner that the motor cannot be operated until complete engagement of the clutches is insured, thereby giving added life to the clutches.

Another advantage arises from the automatic control of the gates whereby the human element is eliminated. Still another advantage arises from the provision of time elements in connection with the solenoid 49 whereby the motor is not operated by a cage passing a floor level.

The term "gates" as used in the claims, as well as the term "shafts," are construed broadly to cover various types of gates and shafts and are not intended to be limited to the particular construction shown.

I claim:

1. An operating mechanism for a plurality of gates, comprising a motor, a normally operative driving connection between the motor and one of the gates, a normally inoperative driving connection between the motor and another of the gates, means for rendering said normally operative connection inoperative and said normally inoperative connection operative, and means for restoring said connections automatically to their original conditions when said last mentioned means becomes ineffective, substantially as described.

2. An operating mechanism for a plurality of gates, comprising a motor, a normally operative driving connection between the motor and one of the gates, a normally inoperative driving connection between the motor and another of the gates, means for simultaneously rendering said normally operative connection inoperative and said normally inoperative connection operative, and means for restoring said connections au-

tomatically to their original conditions when said last mentioned means becomes ineffective, substantially as described.

3. An operating mechanism for a plurality of gates, comprising a motor, a normally operative driving connection between the motor and one of the gates, a spring device cooperating with said connection, a normally inoperative driving connection between the motor and another of such gates, and means for overcoming the action of the spring device for rendering said normally operative connection inoperative and said normally inoperative connection operative, substantially as described.

4. An operating mechanism for a plurality of gates, comprising a motor, a clutch connection between the motor and one of the gates, a clutch connection between the motor and another of the gates, means for simultaneously operating said clutches, said means preventing said clutches from being simultaneously effective, and automatically operable means for simultaneously returning said clutches to their original positions, substantially as described.

5. An operating mechanism for a plurality of gates, comprising a motor, a normally operative clutch connection between the motor and one of the gates, a normally inoperative clutch connection between the motor and another of said gates, means for simultaneously operating said clutches, and automatically operable means for simultaneously returning said clutches to their original positions, substantially as described.

6. An operating mechanism for a plurality of gates, for elevator cages, comprising a motor, means for driving one of said gates by the motor, means for driving another of said gates by the motor, circuit closing devices actuated by the cages for controlling the operation of the motor, means controlled by one of said circuit closing devices for operatively connecting the driving means for one of said gates to the motor, and means for preventing the operation of said motor until after said connection has been made, substantially as described.

7. An operating mechanism for a gate, comprising a motor, a normally inoperative driving connection between the gate and said motor, electrically operated means completely operable throughout one time interval for rendering said connection operative, and means completely operable through a different time interval and effective only after said operative connection is established for rotating the motor, substantially as described.

8. An operating mechanism for a gate, comprising a motor, a clutch connection between the gate and said motor, means for holding said clutch connection in normally inoperative position, electrically operated

means completely operable through one time interval for moving said clutch to operative position, and means completely operable through a different time interval and effective only after the clutch has been moved to operative position for rotating the motor, substantially as described.

9. An operating mechanism for a gate, comprising a motor, means for driving the gate by said motor, an electro-magnetic device controlling said means, a second electro-magnetic device controlling the operation of said motor, and means retarding the operation of said electro-magnetic devices varying amounts to prevent initial concurrent operation of said devices, substantially as described.

10. An operating mechanism for a gate, comprising a motor, means for driving the gate by said motor, an electro-magnetic device controlling said means, a second electro-magnetic device controlling the operation of said motor, and means retarding the operation of said electro-magnetic devices, 25 one of said means retarding the electro-magnetic device controlled thereby a greater amount than the other of said means, substantially as described.

11. A control system for gates, comprising a motor, means for driving one of said gates by said motor, means for driving another of said gates by said motor, a power circuit for said motor, circuit closing devices in said circuit arranged to be operated by said gates to break said circuit, an electro-magnetic reversing switch in said circuit, and means controlling the operation of said reversing switch, substantially as described.

12. An automatic gate mechanism for mine shafts, comprising a gate for each of said shafts, a motor for driving either of said gates, clutch connections between said motor and each of said gates, means completely operable through one time interval for controlling the operation of said clutch connections, and other means controlling the operation of said motor, said last named

means being completely operable through a different time interval whereby the same is effective only after a clutch connection is established, substantially as described.

13. An operating mechanism for a plurality of gates, comprising a motor having a shaft projecting beyond opposite sides thereof, a clutch member on each end of said shaft, a second clutch member cooperating with each of said first mentioned clutch members and each operatively connected to one of said gates, means for normally holding one pair of said clutch members in operative position and the other pair of said clutch members in inoperative position, connections between one of the members of each pair of clutches for moving the same in unison, and electro-magnetic means for moving said last named means to simultaneously engage the clutch members which were in operative position and engage the clutch members which were in inoperative position, substantially as described.

14. An operating mechanism for a plurality of gates, comprising a motor having a shaft projecting beyond opposite sides thereof, a clutch member on each end of said shaft, a second clutch member cooperating with each of said first mentioned clutch members and each operatively connected to one of said gates, means for normally holding one pair of said clutch members in operative position and the other pair of said clutch members in inoperative position, connections between one of the members of each pair of clutches for moving the same in unison, electro-magnetic means for moving said last named means to simultaneously engage the clutch members which were in operative position and engage the clutch members which were in inoperative position, and means retarding the operation of said last named means, substantially as described.

In testimony whereof, I have hereunto set my hand.

CHARLES DRUM.
